DESIGN FOR A LAMP

John J. Wright, Fort Worth, Tex.

Application July 12, 1939, Serial No. 85,977

Term of patent 3½ years

To all whom it may concern:

Be it known that I, John J. Wright, a citizen of the United States of America, residing at Fort Worth, in the county of Tarrant and State of Texas, have invented a new, original, and ornamental Design for Lamps, of which the following is a specification, reference being had to the accompanying drawing, forming part thereof.

The figure is a perspective view of a lamp, showing my new design.

What I claim is:

The ornamental design for a lamp, substantially as shown.

JOHN J. WRIGHT.
